UNITED STATES PATENT OFFICE.

JAMES M. BRYCE, OF PHILADELPHIA, PENNSYLVANIA, ASSIGNOR TO
EDWARD A. GREENE, HENRY L. GREENE, WILLIAM R. GREENE, AND
EDWARD A. GREENE, JR., OF RIVERSIDE, RHODE ISLAND.

DESIGN FOR A HANDKERCHIEF OR BANNER.

SPECIFICATION forming part of Design No. 18,487, dated July 31, 1888.

Application filed June 22, 1888. Serial No. 277,929. Term of patent 7 years.

To all whom it may concern:

Be it known that I, JAMES M. BRYCE, a citizen of the United States, and a resident of Philadelphia, Pennsylvania, have invented a new and original Design for a Flag Handkerchief or Banner, of which the following is a specification.

My design for a handkerchief or banner is fully illustrated in the accompanying drawing, the figure of which is a view of the handkerchief, in which view line-shading takes the place of color.

The design comprises a square central field, A, on which are a number of stars, a, and around this square field are a series of rectangular borders, B, and an outer transversely striped border, D.

I claim—

The within-described design for a handkerchief or banner, said design consisting of the central field, A, with stars a thereon, rectangular borders B, and outer transversely-striped border D, all substantially as described and shown.

In testimony whereof I have signed my name to this specification in the presence of two subscribing witnesses.

JAMES M. BRYCE.
